UNITED STATES PATENT OFFICE.

ROBERT E. HYSERT, OF BUFFALO, NEW YORK, ASSIGNOR OF ONE-HALF TO EDWIN R. DEMPSEY, OF BUFFALO, NEW YORK.

REVERSIBLE WINDOW.

Application filed September 12, 1924. Serial No. 737,406.

This invention relates to a window in which the sash may be reversed or turned in such a position within the frame that both sides of the glass pane can be cleaned from the inside of the room or building and more particularly a window of this character in which two sashes are normally arranged one above the other and mounted side by side in the frame in such manner that these sashes can be slid vertically into a closed or open position.

It is the object of this invention to provide a window of this character which can be organized either as an ordinary single sash transom window in which the sash can be reversed so as to permit of cleaning either side of the same from the interior of the building and also organized as a double hung window in which two sashes are capable of sliding vertically in the frame and each of the sashes reversed or shifted into a position for cleaning the glass of the same from the interior of the building.

Another object of this invention is to so organize a window of this character that the sash may be reversed without removing any screens or storm-sashes which may be applied to the outside of the window opening; also to permit of tilting the sash sufficiently for providing ventilation and causing the fresh incoming air to be directed to the ceiling of the room instead of entering the latter in a horizontal direction and thereby insuring a proper method of ventilation and circulation of the air, and also preventing rain or snow from driving into the room.

A further object of this invention is to so mount the sashes in the window frame that practically the entire window opening may be utilized for obtaining the maximum ventilation; also to mount the sashes in the frame that the same can be removed therefrom and replaced without detaching the usual stops arranged on the window frame, thereby enabling the stops to be permanently applied to the frame and dispensing with the usual screws heretofore employed for detachably connecting these members.

With these objects in view this invention

consists of the organization of the structure which will be hereinafter more fully described.

In the accompanying drawings:

Figure 1 is a vertical transverse section of a window containing upper and lower vertically sliding sashes which are commonly known as double hung windows and in which the sashes are mounted within the frame in accordance with my invention, the sashes in this particular view being shown in their upright and fully closed position.

Figure 2 is a similar view showing the upper and lower sashes tilted inwardly at an angle into a position in which the interior of the room will be ventilated by directing the incoming air toward the ceiling but preventing the entrance of rain or snow into the room.

Figure 3 is a similar view showing the upper and lower sashes turned inwardly into a horizontal position in which they are reversed to such an extent that both sides of the window glass can be cleaned from the inside of the building.

Figure 4 is a fragmentary vertical longitudinal section, on an enlarged scale, taken on line 4-4, Fig. 1.

Figure 5 is a fragmentary horizontal section, on an enlarged scale, taken on line 5-5, Fig. 1.

Figure 6 is a detached side elevation of one form of mounting bar or sliding bar corresponding to the form shown in Figures 1 to 5.

Figure 7 is a similar view showing a slightly modified form of the mounting or sliding bar which can be used in this window structure in place of that shown in Figure 6.

Figures 8, 9 and 10 are horizontal sections taken on the correspondingly numbered lines in Figure 6.

Figures 11, 12 and 13 are horizontal sections taken on the correspondingly numbered lines in Figure 7.

Figure 14 is a fragmentary horizontal section taken on line 14-14, Fig. 3.

Figure 15 is a horizontal section similar to Figure 5 but showing my invention.

tion embodied in a transom window in which the sash is only capable of swinging in a vertical plane for opening and closing the same but is incapable of sliding vertically in the frame.

Similar characters of reference indicate like parts throughout the several views.

Referring to Figures 1 to 5, 8 to 10 and 14:

- 10 The numerals 20, 20 represent the two upright stiles of a window frame in which two sashes are double hung, 21 the upper horizontal head connecting the upper ends of these stiles and 22 the horizontal sill connecting the lower ends of the stiles and provided on the inner part of its upper side with an outwardly facing rabbet or shoulder 23 and above said shoulder or rabbet with an apron 24. On the inner side of each of 20 the stiles the same is provided with an inner stop 25, an intermediate stop or parting strip 26 and an outer stop 27 which form the usual inner and outer vertical runways 28, 29 in which is mounted the means whereby 25 the inner lower sash 30 and the upper outer sash 31 are slidably mounted so as to permit of opening or closing the same by a vertical rectilinear movement thereof. Each of these sashes may be of any suitable construction, that for example shown in Figures 4 and 5 consisting of a wooden frame 19 and a glass pane 32 mounted within the sash frame. In the closed position of the sashes the horizontal meeting rail 33 at the lower 30 end of the upper sash and the horizontal meeting rail 34 at the upper end of the lower sash engage with each other, as shown in Figure 1 and the upper end of the upper sash engages with a horizontal groove formed on 35 the underside of the frame head between the upper horizontal parting strip 35 and the upper outer stop 36 applied to the head, and the lower end of the lower sash is provided with a rabbet 37 whereby the same fits 40 against the upper surface of the frame sill and the shoulder 23 and apron 24, thereby forming a weather-tight joint between these members at the places indicated for excluding rain, wind or snow.
- 45 Between the outer edge of the vertical rail of each of the sashes and the adjacent part of the respective runway of the frame is arranged a mechanism whereby the edge of the respective sash is mounted on the window frame in such manner that the same is 50 capable of sliding vertically thereon and also capable of being tilted at an angle with reference to the frame for ventilating purposes and also moved into a horizontal position with reference to the frame to afford 55 convenient access to opposite sides of the window glass for cleaning the same from within the building. Inasmuch as the several mountings between opposite vertical 60 edges of both sashes and the frame are iden-

tical in construction the following description of one will apply to all of them. Secured to the back of each runway by means of nails 38 or otherwise are two filling or guide strips 39 of wood or other suitable material which strips are spaced apart from each other a considerable distance horizontally so as to form between them a central or intermediate groove 40 which is comparatively wide while the opposite outer sides of these guide strips are spaced apart from the adjacent window stops a comparatively small distance so as to form comparatively narrow guide grooves 41 and 42 between these guide strips and the respective stops, as shown in Figures 1, 2, 3 and 5. The front faces of these guide strips or filling pieces are substantially flush with the front faces of the window stops. Between the front sides of these guide strips and the adjacent vertical outer edge of the respective upright rail of the sash frame is arranged a vertically sliding mounting bar 43 which is preferably constructed of sheet metal which is substantially equal in length and width to the area of the outer face or side of the respective upright rail. On the upper part of its rear side this mounting or sliding bar is provided with a laterally projecting lug 44 which receives the inner depending stretch of a sash cord or line 45, the rear stretch of which is arranged behind the adjacent frame stile and provided at its lower end with a sash counter-balancing weight 46 while the turn between the inner and outer stretches of this sash cord passes over a sash pulley 47 pivotally mounted in an opening in the upper part of the respective sash stile. At its opposite vertical edges the body of this sliding or mounting bar is provided with rearwardly projecting flanges 48, 49 which are arranged in the narrow guide grooves 41, 42 of the adjacent frame stile and are adapted to slide vertically therein and guide the mounting bar during such movement. At its outer vertical edge the body of each sliding or mounting bar is also provided with a vertical channel 50 which opens inwardly or toward the interior of the building. In the lower part of the body 55 of each sliding or mounting bar the same is provided with an upright sash guideway or slot 51 which is preferably formed by bending the metal of this body inwardly along opposite vertical edges of this slot and thereby form guide flanges 52 thereon which project backwardly into the intermediate groove 40 of the frame runway and are adapted to engage with the opposing sides of the guide strips 39. On the upper part of the body 50 of the sliding or mounting bar is arranged a brace guideway or slot having a lower part 53 which is of considerable length while its upper end 54 is comparatively short and enlarged compared with the lower part so 100

that this brace guideway or slot has the general appearance of a key-hole, as shown for example in Figure 6. At the lower end of each sliding or mounting bar the same is provided on its front side with a block 55 secured thereto by means of rivets 56 or the like, which block serves to reinforce this end of the respective sliding or mounting bar and also as a filler between the lower end of this bar and the adjacent lower end of the sash frame.

On the outer vertical edge of each upright rail of a sash the same has secured thereto a facing or weather strip 57 which is constructed of metal and which is secured to this sash rail by means of screws 58 or the like. Adjacent to the outer vertical edge of each sash rail the same is provided with a rabbet 59 which is adapted, in the normally closed position of the sash, to receive the front wall or edge of the respective channel 50. The rear vertical edge of each facing or weather strip 57 projects over a rabbet 59 and forms a vertical fin or tongue 60 which engages with the opening or concave side of the adjacent channel in the closed or normal position of the sash, as shown in Figure 5 and thereby serves to produce a weathertight joint between the sash and frame at this place. The weather strip 57 is let into a longitudinal recess 61 formed on the outer part of the respective upright sash rail and is provided at its inner edge with an outwardly turned flange 62 which abuts against a shoulder 63 formed on the adjacent part of the upright sash rail and thereby strengthens this weather strip and also protects the adjacent edge portion of the upright sash rail against wear. Adjacent to its lower end the facing or weather strip is provided with a laterally projecting pivot pin or trunnion 64 which is adapted to slide vertically in the sash guideway 51 of the adjacent sliding or mounting bar and also to turn in a vertical plane about a horizontal axis therein together with the respective sash on which it is mounted for the purpose of inclining the sash when it is desired to ventilate the room or to turn the sash into a position at right angles to the window frame and the mounting bars for convenience in cleaning the opposite sides of the window panes.

Between each facing or weather strip and the adjacent mounting bar is arranged a brace bar 65 which is preferably constructed of thin flat metal. This bar is pivotally connected at its lower end with the central part of the respective facing or weather strip on the sash by means of a horizontal longitudinal screw 66, or equivalent means. At its upper end this brace bar is provided with a coupling pin which projects laterally therefrom and which has a narrow or reduced neck 67 adapted to slide vertically in

the brace guideway of the mounting bar and terminating in an enlarged head 68 which is adapted to pass through the enlargement 54 at the upper end of the brace guideway and also to engage with the rear side of this guideway on opposite sides of the lower narrow part 53 thereof.

In the normally closed position each sash in which it is arranged upright between its two companion mounting bars, the pivot pins 64 on the lower end thereof engage with the lower ends of the sash guideways 51, the outer vertical edges of the weather strips 57 engage with the inwardly opening channels 50 of the mounting bars, the brace bars 65 are arranged in an upright position between the weather strips 57 and the upper parts of the mounting bars, and the coupling pins at the upper ends of the brace bars are arranged within the enlarged upper ends of the brace guideways 53, as shown in Figures 1, 4 and 5. When it is desired to merely incline or tilt the sashes for the purpose of ventilating the room and directing the fresh air toward the ceiling while preventing the entrance of rain, snow or wind horizontally into the room, the lower sash need only be pulled inwardly at its upper end so that the same turns at its lower end about the pivot pins 64 as an axis. Upon operating the sash in this manner the extreme lower end of this sash moves away from the outwardly facing abutment on the window sill formed by the shoulder 23 and the apron 24. The movement of the sash in this direction is limited by its brace bars 65 which at this time move inwardly at their lower ends with the sash so that they assume an incline position, and during this time the reduced parts of the coupling pins at their upper ends slide downwardly in the narrow parts 53 of the brace guideways and the enlarged heads 68 of the latter engage behind the respective lower part of these guideways until the necks of these coupling pins engage the lower ends of the brace guideways 53, as shown in Figure 2. When the parts are in this position the upper end of the lower sash is held against further inward movement and the upper ends of the brace bar are prevented from becoming detached from the mounting bars.

If it is now desired to open a sash to its maximum extent so as to afford the fullest ventilation of the room and also permit easy access to both sides of its glass the lower end of the respective sash is raised so that it turns about a horizontal axis formed by the connecting pins 66 and at the same time the pivot pins 64 slide upwardly in the sash guideways 51 of the mounting bars until they engage with the upper end thereof, as shown in Figure 3, at which time this sash is arranged in a horizontal position and provides the maximum ventilation and per-

mits of cleaning both sides of its glass from the interior of the building. While thus turning the sash from its upright position into either an inclined position, as shown in Figure 2, or into a horizontal position, as shown in Figure 3 the fins 60 at the outer vertical edges of the weather strips 57 are disengaged from the channels 50. When the sashes are shifted into an inclined position, as shown in Figure 2, the lower outer corners of the weather strips still remain in engagement with the channels 50 so as to maintain a connection between the same in this position. In order to also maintain a connection between the weather strips and the mounting bars when the sash is moved into a horizontal position each of the weather strips is provided at its lower end with a lip 69 which projects downwardly below the adjacent pivot pin 64 and is adapted to engage with the adjacent part of the channel 50, as shown by dotted lines in Figure 3 and by full lines in Figure 14, thereby maintaining the weather strip and the mounting bar in such relation so that upon again closing the sash the outer longitudinal edges or fins 60 of the weather strips will be guided into the remaining parts of the channels 50 so as to properly re-engage the same for forming a weather-tight joint between the respective parts.

If it is desired to wholly remove either of the sashes from the frame and the mounting bars this can be done by raising the inner end of this sash while in its horizontal position sufficiently to bring the coupling pins of its brace bars 65 in line with the upper enlarged ends 54 of the brace guideways 53, in which position the enlarged heads 68 of these brace bars may be withdrawn forwardly through the enlargements 54 and thereby wholly detach the brace bars 65 from the mounting bars. To also permit the lower ends of the weather strips 57 to be detached from the channels 50 while the sash is in a horizontal position a sufficiently loose fit is provided between the pivot pins 64 and the upper parts of the sash guideways 51 to permit these pivot pins 64 to move inwardly an extent sufficient to disengage the lower ends of the weather strips 57 from the channels 50. This is preferably accomplished by making the sash guideways 51 somewhat wider than the diameter of the pivot pins 64. To accomplish this purpose it is only necessary to enlarge the upper part of the guideways 51 but for convenience in manufacture the same are enlarged throughout their entire height, as shown in Figures 2, 3 and 14. After the brace bars 65 have been detached from the mounting bars 43 and the lower ends of the weather strips 57 have been disengaged from the sash guideways 51, in the manner described, it is now only necessary to tilt the sash in

a plane parallel with the face of the window frame or in other words at right angles to the plane in which the same is turned for moving the same into an inclined ventilating position or into a horizontal cleaning position. When thus tilted both pivot pins 64 can be disengaged from the guideways 51 and thereby the sash can be wholly detached from the frame for convenience in repairing or inspecting the same when this becomes necessary.

A reversal of the operations just described will enable the sash to be again operatively mounted on the mounting bars so that the same can be again swung upwardly into its normal vertical position and then opened and closed more or less in the manner in which this is commonly known in double hung windows of this type. By first moving the upper sash downwardly so that its upper end clears the upper intermediate and outer horizontal stops 35 and 36 it is possible to open this sash into an inclined position for ventilating purposes, as shown in Figure 2 and to swing the same into a horizontal position for cleaning purposes, as shown in Figure 3, in substantially the same way as this can be done when operating the lower sash in the manner previously described.

Instead of constructing the sliding or mounting bar so that the same has a flat body as shown in Figures 1 to 6 and 8 to 10 the same may be stamped out of sheet metal in the form shown in Figures 7, 11, 12 and 13. In this last mentioned form of the sliding or mounting bar the same is stamped out of sheet metal so that the body 70 of the same is provided with a vertical longitudinal channel 71 between its opposite longitudinal edges which opens forwardly. The lower part of this channel is utilized to form a sash guideway 72 corresponding to the guideway 51 in the construction shown in Figure 6. In this modified form of the sliding or mounting bar the downward movement of the pivot pin 64 in the guideway 72 is limited by means of a block 73 which is secured to the adjacent part of this mounting bar by means of rivets 74 and which also serves as a means of reinforcing or strengthening this end of the bar. The upward movement of the pin 64 in this sash guideway 74 is limited by means of a clip 75 secured in the bottom of the channel 71 by means of rivets 76. In this modified construction the lower and upper parts 54 of the slot forming the brace guideway are formed in a separate piece of metal 77 which is made of U-shaped form in cross section and secured in the upper part of the channel 71 by brazing or otherwise. On its upper rear part the channel portion 71 is provided with a rearwardly projecting web 78 provided with a hole 79 to permit of attaching thereto the front

stretch of the sash cord in a manner similar to that shown in Figure 4.

When this invention is embodied in a window of the transom type in which the sash does not slide vertically in the frame but is only capable of swinging in a vertical plane therein into its open and closed position, the means for mounting the sash in the frame in accordance with my invention may be organized in the manner shown in Figure 15. In this construction the filling strips or pieces 80 may be permanently secured by means of nails 81 or otherwise to the back of the vertical channel 82 on the frame stile 20 and the mounting bar 83 may be permanently secured by means of screws 84 or other suitable means to the filling strips 80. In this construction the opposite vertical edges of the mounting bar are not provided with guide flanges 41, 42 as in the construction shown in Figures 1 to 6 and 8 to 10 inasmuch as no guiding means for the mounting bar are necessary in this case. In this modified construction the vertical sash guide slot 25 has its opposite vertical edges bounded by rearwardly projecting flanges 85 which are formed on the adjacent parts of the body of the mounting bar by folding or doubling the metal upon itself, as shown in Figure 15.

In all essential features however of the construction shown in Figure 15, the same is substantially like that shown in Figures 1 to 6 particularly the manner of mounting the lower end of the sash on the mounting bars 35 so as to be capable of sliding vertically thereon and also swinging in the vertical plane relatively thereto; also the means of connecting the upper part of the sash with the mounting bars by means of the pivoted braces so as to hold the sash either in a partially opened inclined position or in a horizontal full open position, as well as permitting the sash to be wholly removed from the mounting bars; and also the means for 40 producing a weather-tight joint between the facing strips at opposite edges of the sash and the channels 50 on the mounting bars. In fact the only substantial difference between the construction of my invention when 45 embodied in a vertically sliding sash and one incapable of sliding vertically is that in the former case the mounting bars are capable of sliding in runways on the window frame while in the latter case the mounting bars are incapable of sliding vertically but are fixedly mounted on the window frame in the channels thereon.

Although this invention is illustrated in the drawings as applied more particularly to a window frame and sash in which the principal parts or members are made of wood it will be obvious that this invention is equally applicable to windows in which the frames and sashes are constructed of sheet

metal without involving any departure from 65 the essence of this invention.

This manner of mounting the sashes in the window frame not only permits of a better ventilation of the interior of a room without permitting rain, wind and snow to drive into 70 the same as well as enabling the glass to be cleaned more conveniently without getting on the outside of the building, but the same also permits of opening the sashes for 75 ventilating and cleaning purposes by a vertical swinging motion of the same without interfering with screens or storm-sashes which may be applied to the outer side of the window frame. Moreover the construction of these means of mounting the sashes in the 80 window frame are such that the same will operate efficiently and without binding or cramping the parts even though the sashes may be warped slightly inasmuch as such warping does not influence any of the members of the mounting mechanism. Furthermore this mounting is so designed that the same is practically weatherproof and operates to effectively prevent the entrance of 85 rain, wind or snow into the building when 90 the sashes are closed and also produces a tight joint between the sashes and the frame so that no rattling will occur when subject to winds or storms.

I claim as my invention:—

1. A window comprising a frame having vertical stiles on its opposite sides, mounting bars arranged in front of the stiles of said frame and each provided on its lower end with a vertical sash guide slot and on its upper end with a brace guide slot having a narrow lower part and an enlarged upper end and a vertical weather channel at its outer edge which opens inwardly, a sash arranged within said frame, weather strips arranged 100 on opposite vertical edges of said sash and each having an outwardly projecting outer edge forming a vertical fin which is adapted in the normal position of the sash to engage with the respective channel; pivot pins arranged on the lower parts of the weather strips and engaging with said sash guide slots, brace bars adapted normally to be arranged between the weather strips and said mounting bars and each pivotally connected 105 at its lower end with the central part of the adjacent weather strip, and coupling pins arranged at the upper ends of the brace bars and each having a reduced neck adapted to move in the brace guide slot of one of said 110 mounting bars and an enlarged head adapted to engage with the rear side of said mounting bar and to pass through the enlarged upper end of the brace guide slot.

2. A window comprising a frame having 115 vertical stiles on its opposite sides, mounting bars arranged in front of the stiles of said frame and each provided on its lower

end with a vertical sash guide slot and on its upper end with a brace guide slot having a narrow lower part and an enlarged upper end and a vertical weather channel at its 5 outer edge which opens inwardly, a sash arranged within said frame, weather strips arranged on opposite vertical edges of said sash and each having an outwardly projecting outer edge forming a vertical 10 fin which is adapted in the normal position of the sash to engage with the respective channel, pivot pins arranged on the lower parts of the weather strips and engaging with said sash guide slots, brace bars 15 adapted normally to be arranged between the weather strips and said mounting bars and each pivotally connected at its lower end with the central part of the adjacent weather strip, and coupling pins arranged 20 at the upper ends of the brace bars and each having a reduced neck adapted to move in the brace guide slot of one of said mounting bars and an enlarged head adapted to engage with the rear side of said mounting 25 bar and to pass through the enlarged upper end of the brace guide slot, each of said weather strips extending at its lower end below the companion pivot pin and forming a locking lip which is adapted to engage 30 the adjacent part of the adjacent channel upon swinging the sash into an open position about the axis of said pivot pins.

3. A window comprising a frame having vertical stiles on its opposite sides, mounting bars arranged in front of the stiles of said frame and each provided on its lower end with a vertical sash guide slot and on its upper end with a brace guide slot having a narrow lower part and an enlarged 40 upper end and a vertical weather channel at its outer edge which opens inwardly, a sash arranged within said frame, weather strips arranged on opposite vertical edges of said sash and each having an outwardly 45 projecting outer edge forming a vertical fin which is adapted in the normal position of the sash to engage with the respective channel, pivot pins arranged on the lower parts of the weather strips and engaging with 50 said sash guide slots, brace bars adapted normally to be arranged between the weather strips and said mounting bars and each pivotally connected at its lower end with the central part of the adjacent weather strip, and coupling pins arranged 55 at the upper ends of the brace bars and each having a reduced neck adapted to move in the brace guide slot of one of said mounting bars and an enlarged head adapted to 60 engage with the rear side of said mounting bar and to pass through the enlarged upper end of the brace guide slot, each of said mounting bars being constructed of sheet metal, and filling pieces arranged between said mounting bars and secured to said frame.

4. A window comprising a frame having vertical stiles on its opposite sides, mounting bars arranged in front of the stiles of said frame and each provided on its lower end with a vertical sash guide slot and on its upper end with a brace guide slot having a narrow lower part and an enlarged upper 65 end and a vertical weather channel at its outer edge which opens inwardly, a sash arranged within said frame, weather strips arranged on opposite vertical edges of said sash and each having an outwardly projecting outer edge forming a vertical fin 70 which is adapted in the normal position of the sash to engage with the respective channel, pivot pins arranged on the lower parts of the weather strips and engaging with said sash guide slots, brace bars 75 adapted normally to be arranged between the weather strips and said mounting bars and each pivotally connected at its lower end with the central part of the adjacent weather strip, and coupling pins arranged at the 80 upper ends of the brace bars and each having a reduced neck adapted to move in the brace guide slot of one of said mounting bars and an enlarged head adapted to 85 engage with the rear side of said mounting bar and to pass through the enlarged upper end of the brace guide slot, each of said mounting bars being constructed of sheet metal, and filling pieces arranged between 90 said mounting bars and secured to said frame.

5. A window comprising a frame provided on the inner side of each of its stiles with a vertical channel, filling strips arranged in these channels, mounting bars 100 having backwardly projecting flanges projecting into said channels and arranged alongside of said filling strips, and a sash movably mounted on said mounting bars.

6. A window comprising a frame having vertical stiles, mounting bars arranged along said stiles and each provided at one end with a sash guide-way and at its opposite end with a brace guideway, a sash arranged between said mounting bars, each provided at one end with a pivot which is adapted to slide lengthwise in one of said sash guide-ways and also turn in the outer end thereof, and braces each pivoted at one end on said sash and slidable at its opposite end in one of said brace guide-ways, each of said sash guideways extending from an end of the respective mounting bar to the cen- 115 120 125

tral part thereof and permitting the sash to be shifted into a fully open position at right angles to the mounting bars.

7. A window comprising a frame having 5 vertical stiles, mounting bars arranged along said stiles and each provided at one end with a longitudinal sash slot and at its opposite end with a longitudinal brace slot, a sash arranged between said mounting bars, pivots arranged at one end of said sash and each engaging one of said sash slots, and braces each pivoted at one end on said sash and slidingly engaging its opposite end with one of said brace slots, each of said sash 10 guideways extending from an end of the respective mounting bar to the central part thereof and permitting the sash to be shifted into a fully open position at right angles to the mounting bars.
- 15 8. A window comprising two supports each of which is provided at one end with a longitudinal sash guide-way and at its opposite end with a longitudinal brace guide-way, a sash arranged between said supports, pivots arranged at one end of the sash and 20 each engaging one of said sash guide-ways, and braces each pivoted at one end on the sash and slidingly engaging its opposite end in the brace guide-way of one of said supports, said sash guide-ways being comparatively long and said brace guideways being comparatively short and each of said sash guideways extending from an end of the respective support to the central part thereof and permitting the sash to be shifted into a 25 fully open position at right angles to the supports.

sash and slidingly engaging its opposite end in the brace guideway of one of said supports, each of said sash guideways extending 30 from an end of the respective support to the central part thereof and permitting the sash to be shifted into a fully open position at right angles to the supports.

9. A window comprising two supports 35 each of which is provided at one end with a longitudinal sash guide-way and at its opposite end with a longitudinal brace guide-way, a sash arranged between said supports, pivots arranged at one end of the sash and 40 each engaging one of said sash guide-ways, and braces each pivoted at one end on the sash and slidingly engaging its opposite end in the brace guide-way of one of said supports, said sash guide-ways being comparatively 45 long and said brace guideways being comparatively short and each of said sash guideways extending from an end of the respective support to the central part thereof and permitting the sash to be shifted into a 50 fully open position at right angles to the supports.

In testimony whereof I affix my signature.

ROBERT E. HYSERT.
